DESIGN FOR A FIREARM

Eugene G. Reising, Hartford, Conn.

Application August 3, 1942, Serial No. 107,802

Term of patent 14 years

To all whom it may concern:

Be it known that Eugene G. Reising, a citizen of the United States, residing at Hartford, in the county of Hartford and State of Connecticut, have invented a new, original, and ornamental Design for Firearms, of which the following is a specification, reference being had to the accompanying drawing forming part thereof.

Fig. 1 is a side elevational view of a firearm showing my new design,

Fig. 2 is a top plan view, and
Fig. 3 is a rear elevational view thereof, the
magazine auxiliary grip being omitted for con-
venience of illustration.

I claim:

The ornamental design for a firearm, as shown.

EUGENE G. REISING.
